A. W. SCHANK.

GREASE INJECTOR FOR FILLING DIFFERENTIAL GEAR CASINGS.

APPLICATION FILED JAN. 21, 1919.

1,318,414.

Patented Oct. 14, 1919.

UNITED STATES PATENT OFFICE.

AETHUR W. SCHANK, OF CAMDEN, NEW JERSEY.

GREASE-INJECTOR FOR FILLING DIFFERENTIAL-GEAR CASINGS.

1,318,414.

Specification of Letters Patent. Patented Oct. 14, 1919.

Application filed January 21, 1919. Serial No. 272,222.

To all whom it may concern:

Be it known that I AETHUR W. SCHANK, a citizen of the United States, residing at Camden, in the county of Camden and State 5 of New Jersey, have invented new and useful Improvements in Grease-Injectors for Filling Differential-Gear Casings with Grease and other Parts of Automobiles and other Machinery, of which the following 10 is a specification.

My invention relates to a new and useful improvement in grease injectors for filling differential gear casings and other parts of automobiles and other machinery, and has 15 for its object to provide an exceedingly simple and effective device of this description adapted to be operated by compressed air provided with convenient mechanism for turning on and shutting off the compressed 20 air so as to start and stop the ejection of grease.

A still further object of my invention is to provide a simple and effective means of filling the container with grease.

With these ends in view, this invention 25 consists in the details of construction and combination of elements hereinafter set forth and then specifically designated by the claims.

In order that those skilled in the art to which this invention appertains may understand how to make and use the same, I will describe its construction in detail referring by numerals to the accompanying drawing 35 forming a part of this application in which:—

Figure 1, is a broken away section of an injector made in accordance with my improvement; and

Fig. 2, is a plan view thereof.

In carrying out my invention as here embodied 1 represents the grease container having a head 2 securely fitting thereto or formed therewith and this head in turn has 45 secured thereto a barrel 3, the outer end of which is threaded to receive the nipple 4.

5 represents the ejector piston which is fitted to slide within the container and has secured thereto the rod 6 which projects 50 rearward into the barrel 3 and has secured upon this inner end the air piston 7, the latter being fitted to slide within said barrel.

A plug valve 8 is fitted within the nipple having the passageway therethrough in 55 alinement with the passageway 10 through

the nipple and the outer end of said nipple is provided with screw-threads 11 for the reception of a coupling for attaching an air pipe to the nipple so as to convey compressed air from a suitable reservoir or 60 source to the injector.

The upper end of the valve 8 carries an arm 12 to which is pivoted at 13 connecting rod 14 which in turn is pivoted at 15 to the arm 16.

The arm 19 is carried upon the lower end of the short spindle 17 which latter is journaled in the lug 18 projecting from the handle 19, and this handle is formed with or secured to the container.

20 represents the hand lever carried by the upper end of the short spindle 17 projecting to one side of the handle 19 having a spring 21 interposed between it and said handle so as to normally hold said lever 70 away from the handle as shown in Fig. 2.

This arrangement enables the user of the injector to open and close the plug valve 2 by pressing against the hand lever 20 thus admitting compressed air to the barrel or 80 cutting the same off therefrom for the purpose hereinafter set forth.

To the front end of the container 1 is secured the head or closure 22 by means of the hinge 23 so that this head may be swung 85 open for filling the container with grease. In order that the head 22 may be firmly locked when closed I pivot a latch 24 at 25 to the head, said latch having a prong 26 which rides over a lug 27 projecting from 90 the side of the container.

To prevent leakage of the grease when under pressure I insert a soft packing 28 of rubber, leather, cork and the like.

To facilitate the filling of gear casings and other grease receptacles I provide a nozzle 28 which is secured to or formed with the head 22 having a passageway leading from the interior of the container.

From the foregoing description the operation of my improved injector will be obvious as follows:

The piston 5 being moved to the rear end of the container, the container being filled with grease, and the head 22 closed and locked, a pipe leading from a compressed air source is then attached to the threads 11 of the nipple when the device is ready for use. Now by grasping the handle 19, inserting the nozzle in the grease receptacle to be 110

filled and pressing upon the hand lever 20 so as to open the valve 8, compressed air will flow into this barrel back of the plunger 17 exerting sufficient pressure thereon to force 5 the piston 5 outward and in so doing eject grease from the nozzle into the desired receptacle. When the proper amount of grease has been delivered to the desired receptacle 10 the lever 20 is released, the spring 21 forcing it sidewise from the handle and thereby closing the valve through the mechanism before described, thus stopping the further delivery of grease.

Of course, I do not wish to be limited to 15 the exact details of construction as herein shown as these may be varied with the limits of the appended claims without departing from the spirit of my invention.

Having thus fully described my invention 20 what I claim as new and useful is:—

1. In a device of the character described, a container for holding a lubricant, a nozzle for delivering the lubricant from the container, a barrel projecting from the rear end 25 of the container, a plunger fitted to slide in the container, a secondary plunger fitted to slide within the barrel, a rod connecting the two plungers, a nipple carried by the outer end of the barrel and a valve located in said 30 nipple, a handle carried by the container, a

mechanism leading from the handle to the valve for operating the latter to admit compressed air to the barrel back of the second plunger.

2. In a device of the character described a 35 container, a closure hinged thereto, means for locking said closure in its closed position, a nozzle projecting outward from the closure and communicating with the interior of the container, a barrel projecting rearward from the container, a plunger fitted to slide in the container, a plunger fitted to slide in the barrel, a rod connecting the two plungers, a nipple carried upon the outer 40 end of the barrel, said nipple having screw threads upon the outer end thereof for the attachment of an air pipe, a valve fitted in the nipple and adapted to open and close the passage way therethrough, an arm carried by the upper end of the valve, a spindle carried by the container, an arm carried by the lower end of the spindle, means for connecting said arms together, a hand lever carried by the upper end of the spindle, means for forcing the hand lever in one direction, and 45 a handle for manipulating the device. 50

In testimony whereof I have hereunto affixed my signature.

ARTHUR W. SCHANK.
